METHOD OF AND APPARATUS FOR
TREATING DIES

Harry Blount, Baltimore, Md., assignor to Western Electric Company, Incorporated, New York, N. Y., a corporation of New York

Application May 20, 1936, Serial No. 80,707

8 Claims. (Cl. 51—217)

This invention relates to a method of and apparatus for treating dies and more particularly to a method of and apparatus for grinding or lapping a wire drawing die comprising two complementary members having opposed arcuately concave drawing faces.

In the manufacture of metallic strands for various purposes where special irregular cross sections are required having one transverse dimension considerably greater than another at right angles thereto, and where such strands are made from circularly cylindrical wire, it is found in some instances to be desirable to convert the circularly cylindrical wire into elliptically or ovaly cylindrical wire as a preliminary step before rolling or drawing into the final irregular form. An illustrative example of such procedure may be found in the manufacture of copper wire or tape having a Z-shaped cross section such as is used in the manufacture of certain types of electrical coaxial conductor cable. For use in drawing such flattened wire from circularly cylindrical stock it has been found advantageous to use a two part die comprising two complementary members having opposed circularly arcuate concave working faces which together have a cross section of the form known in geometry and in architecture as the "vesica piscis". Such dies and their use form no part of the present invention but are the subject of copending application Serial No. 80,706, filed May 20, 1936 by the present inventor.

An object of the present invention is to provide a method of and apparatus for making and restoring the working or drawing surfaces of the members of a die in a simple, convenient and accurate manner and by means of simple, rugged and reliable apparatus.

There is no other name for the figure formed by two intersecting circular arcs each concave toward the other than "vesica piscis". For the present therefor and for use in this specification and the claims appended thereto, the words "vesica" and "vesicate" are defined to mean the vesica piscis and having the form of the vesica piscis respectively.

In one embodiment, the invention contemplates a rigid body member adapted to be held in a lathe or other rotary working apparatus, the body being provided with an axial aperture to receive a suitably formed lapping or grinding tool, and having complementary recesses on opposite sides of the aperture with means to hold the two complementary members of a two part vesicate die

rigidly with their circularly arcuate working surfaces coaxial with the aperture.

Other objects and features of the invention will appear from the following detailed description of one embodiment thereof taken in connection with the accompanying drawing in which the same reference numerals are applied to identical parts and in which

Fig. 1 is a view in front elevation of a device for working vesicate die members constructed in accordance with the invention;

Fig. 2 is a view thereof in section on the line 2—2 of Fig. 1;

Fig. 3 is a side view of a lap for use therewith;

Fig. 4 is a view on a smaller scale similar to Fig. 1 of a modified form;

Fig. 5 is a sectional view on the line 5—5 of Fig. 4, and

Fig. 6 is an enlarged detached view in perspective of one of the detachable separating members shown in Fig. 5.

The device which is the embodiment of the invention as herein disclosed comprises a body 40 preferably generally cylindrical and having a coaxial cylindrical diminished rear portion 41 adapted to be gripped to the chuck of a lathe or other rotary working tool. The body 40 also has a central axial bore 42 adapted to provide clearance behind work held in the body as hereinafter described for a lapping or grinding tool 43 to be held in a tailstock or the like on the lathe.

In the front face of the body 40 is a pair of complementary recesses 44 and 44, a description of one of which and its appurtenances will suffice for both. The recess 44 has straight, parallel horizontal upper and lower walls connected by semicircularly cylindrical end walls, and a flat vertical rear wall 45. The left hand semicylindrical end wall is the forward continuation of half of the cylindrical inner surface of a bore 46 extending into the body from the rear wall 45. A cylindrical stop pin 47 is housed in the bore 46 and extends out beyond the wall 45 into the recess 44, and is formed at its outer portion with a flat lateral stop surface or facet 48, a tapped radial bore 49 extends from the outer surface downwardly through the upper wall of the recess at its center and houses a correspondingly threaded screw 50. A tapped bore 51 extends horizontally out from the center of the right hand semicylindrical end wall of the recess through the peripheral surface of the body and houses a correspondingly threaded screw 52. In the lower half of the body the elements 44 to 52 inclusive,

55

correspond respectively to the elements 44 to 52 inclusive of the upper half.

The two complementary members of a vesicate die to be lapped are shown in position in the device in Figs. 1 and 2. The upper member comprises a substantially rectangularly parallelo-pipedal body 22, preferably of suitably heat treated steel, in which is mounted an insert 24, preferably of tungsten carbide. The conical working faces 34 and 35 and the cylindrical working face 36 are formed wholly on the insert while the relief face 37 is formed partly on the insert and partly on the body 22. The two die halves are complementarily identical and in use are placed abutted together with their inserts toward each other so that the aperture between them defined by the circularly arcuate facets 34, 35, 36 and 37 is vesicate in form.

In the device 40 the wall 53 between the recesses 44 and 144 is of such carefully predetermined thickness, that when the die members are locked against the wall 53 and against the stop faces 48 and 148, the circularly arcuate facets 34, 35, 36 and 37 of both inserts 24 and 25 all have their centers in the axis of the bore 42 which is also the axis of the cylindrical periphery of the body portion 41. Hence when the whole assembly is chucked in a lathe or the like by means of the portion 41, the working facets of the inserts will revolve accurately about their own centers, and if a lapping tool such as is illustrated in Fig. 3 be held coaxially in and between the inserts 24 and 25, it will have precisely the desired and intended effect of affecting the entire surface of the particular facet matched by its taper on both inserts simultaneously and evenly.

Thus a rough cut pair of new die members may be ground and lapped to size and polish in one operation and with one tool simultaneously as to each facet, thereby ensuring identity of the two halves as to shape. Furthermore this method and apparatus enables the manufacture with simple rotary procedure of a die having a non-circular hole avoiding all the uncertainties and dissymmetry and time consumption consequent upon grinding and polishing with a reciprocating wire or other strand.

When a pair of such vesicate die members is too worn for further use their abutting faces may be cut back by the trifling amount necessary, and new facets of the same form and dimensions may be cut by the use of the device 40, thus restoring the dies. Or the dies may be recut in the device 40 without cutting back their abutting faces, but with a larger tool 43 for use on a larger size of stock.

A slightly modified form of the device is disclosed in Figs. 4, 5 and 6, in which the separating walls 53 between the recesses 44 and 144 and integral with the body 40, of Figs. 1 and 2 are replaced by removable and interchangeable members or blocks 253 attached to and accurately positioned on the body 40 by means of dowels 54 and screws 55. The enlarged inner portions 56 of the members 253 may be made of a width appropriate to the curvature of a given pair of inserts 24 and 25, and thus by interchange of the members 253 the device may be adapted to properly hold paired inserts for grinding of a considerable range of curvature.

It is to be noted that while the disclosure is of a pair of inserts 24, 25 having their arcuate faces of the same radius, the invention is not confined to this condition. So long as the chords of the two arcs are of the same length, their radii may have any value within this last limitation and the

sagittas of the two arcs need not be equal. In any case however the width of the wall 53 or member 253 between the inserts must be equal to the sum of the radii of the two arcs diminished by the sum of the sagittas. If the two inserts have arcs of different radii they will be set in the device and treated one at a time.

The embodiments of the invention herein disclosed are illustrative only and may be widely modified and departed from in many ways without departing from the spirit and scope of the invention as pointed out in and limited only by the appended claims.

What is claimed is:

1. A rotatable cylindrical device for holding members of a non unitary die each having an arcuate working facet thereon, which device comprises a body having two parallel recesses symmetrically disposed therein with respect to its periphery to receive the two members, a wall between the two recesses of such thickness as to space the members with their arcuate facets coaxial with each other, means to clamp the members against the wall, and means to position and clamp the members in alignment with each other. 15 20 25

2. A rotatable cylindrical device for holding members of a non unitary die each having an arcuate working facet thereon, which device comprises a body having two parallel recesses symmetrically disposed therein with respect to its periphery to receive the two members, a block between the two recesses to space the die members apart and of a width equal to the sum of the radii of the opposed arcuate facets diminished by the sum of the sagittas of the facets, means to clamp the die members against the spacing block, and means to position and clamp the members in alignment with each other. 30 35

3. A device for holding members of a non-unitary die each having an arcuate working facet 40 thereon, which device comprises a body having two parallel recesses therein to receive the two members, a stop in each recess to be abutted by one end of a die member in that recess, a screw mounted in the body to force each die member 45 against its stop, a wall between the two recesses of such thickness as to space the members with their arcuate facets coaxial with each other, and a screw mounted in the body to force each die member against the wall. 50

4. A method of treating a die having a plurality of parts each having an arcuate working facet thereon, which method comprises positioning two parts of the die with their arcuate facets coaxial with each other, and applying a single 55 grinding means to the plurality of arcuate facets simultaneously.

5. A method of treating a die having a plurality of parts each having an arcuate working facet thereon, which method comprises positioning two parts of the die with their arcuate facets coaxial with each other, and applying a single rotary grinding means simultaneously to the several arcuate facets, the parts being so proportioned and arranged that each facet while being ground also serves to support the grinding means 60 65 to grind another facet.

6. A method of treating a die having two mutually abutting parts each having an arcuate working facet on that face thereof which abuts 70 against the other part to coact with the facet thereon, which method comprises cutting back the mutually abutting faces of the parts, positioning two parts of the die with their arcuate facets coaxial with each other, and applying a 75

single grinding means to the arcuate facets simultaneously.

7. A method of treating a die having two mutually abutting parts each having an arcuate working facet on that face thereof which abuts against the other part to coat with the facet thereon, which method comprises cutting back the mutually abutting faces of the parts, positioning two parts of the die with their arcuate facets coaxial with each other, and applying a single rotary grinding means simultaneously to the several arcuate facets, the parts being so proportioned and arranged that each facet while being ground also serves to support the grinding means to grind another facet.

10 8. A device for treating members of a non-

unitary die each having an arcuate working facet thereon, which device comprises a body having two parallel recesses therein to receive the two members, a wall between the two recesses of such thickness as to space the members with their arcuate facets coaxial with each other, means to clamp the members against the wall, and means to position and clamp the members in alignment with each other, in combination with rotary grinding means dimensioned to enter between the arcuate working facets to grind the same simultaneously, the parts being so proportioned and arranged that each facet while being ground also serves to support the grinding means to grind another facet.
